<img alt="A detailed technical cross-sectional diagram of a mechanical device, labeled Fig. 2. The diagram shows a complex assembly of various parts, including a main housing (1), a piston (2), a connecting rod (3), and a crankshaft (4). Numerous numbered callouts point to specific components: 5, 7, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, TELEPHONE DIAL

Willy Lohs, Walter Paul, and Heinrich Kallhardt, Munich, Germany, assignors to Siemens & Halske Aktiengesellschaft, Munich, Germany, a corporation of Germany

Filed Sept. 2, 1958, Ser. No. 758,522

Claims priority, application Germany Sept. 10, 1957

9 Claims. (Cl. 179—90)

This invention is concerned with a telephone call transmitter of the finger-wheel or finger-disk operated type, provided with an impulse transmitting device and a governor for regulating the operation thereof.

In known transmitters of the above indicated kind, the spindle for the governor, which is actuated by a worm drive, is disposed perpendicular to the spindle for the impulse transmitting device. The assembly of dials of this kind is involved because it requires keeping of accurate tolerances. The worm drive is moreover relatively inefficient because part of the force applied for rotation is dissipated in the form of axially effective components.

There is also a call transmitter known in which the drive for the governor and for the impulse device is effected over a two-stage-spur gear wheel. The spindles for this drive are provided with extensions which are journaled in two plates. The assembly of such transmitter device is likewise very involved because the two plates must be adjusted accurately one with respect to the other and their structure must be of highest accuracy. Such a device exhibits the further disadvantage that access to the gear parts is difficult and that one of the plates must be removed to effect exchange or replacement of individual parts.

The object of the invention is to provide a telephone call transmitter which is characterized by simple assembly, easy accessibility of gear parts and reliable operation, without requiring any particular maintenance. This object is realized by disposing the spindles for the gears with one end thereof secured in the mounting frame or base and freely extending from such base.

The disposition of the spindles with the associated gear parts freely extending from the base may be effected very simply. The gear parts are in the assembled device very well accessible. In accordance with a further feature of the invention, the assembly is simplified by embedding the spindles in the base or frame incident to fabrication of the latter, for example, as a diecast part.

Maintenance of the gears becomes practically superfluous by forming the operating parts of all gear wheels and pinions of non-metallic synthetic material, thus eliminating the lubrication required in the case of metallic gear wheels. The spindle of the finger disk and the drive gear wheel are coated with a non-metallic synthetic material, thereby securing proper operation of such spindle in the base without requiring bearing sleeves made of bronze or the like inserted in the base. The spindle may moreover be made as a diecast part, thereby reducing the cost of fabrication.

The stop for limiting the rotation of the finger disk is disposed in the marginal portion thereof, whereby the gears are stopped with little stress since the mass forces to be controlled appear at points where the stop for limiting the rotary motion is disposed.

The foregoing and further objects and features of the invention will appear in the course of the description which is rendered below with reference to the accompanying drawing, wherein

FIG. 1 is a bottom plan view of the interior parts of a call transmitter device according to the invention; and

FIG. 2 is a sectional view thereof taken approximately on the line 2—2 of FIG. 1.

2

Referring now to the drawing, numeral 1 indicates a diecast frame or base in which are embedded spindles 2 and 3. The spindle 2 serves for journaling the governor and the spindle 3 for journaling the impulse transmitting device. The frame comprises an extension 4 which embraces the governor spindle 2 approximately semicylindrically, such extension serving for securing the member 7 which forms a cylindrical raceway for the governor, the member 7 being stamped from a plate, and being fastened by means of screws 5 and 6.

Rotatably journaled in the frame is the main shaft 9 which is fixedly connected with the finger disk 8. This shaft is provided with a placket of non-metallic synthetic material 10. The good slipping properties of the synthetic material (a polyamide will preferably be used) make it unnecessary, as already mentioned before, to insert individual bearing bushings in the frame and make it possible to form the shaft as a diecast part, resulting in simplification of assembly operations and in reduction of costs.

At its free end, the main shaft 9 is provided with a casing 12 secured to the shaft by means of an angular member 11, the casing 12 containing restoring spring 13, one end of which is anchored in the frame while the other end is anchored in the casing 12. The spring casing 12 is provided with extensions 14 which project through openings 15 formed in a gear wheel 17 disposed adjacent the casing 12 and rotatably secured in place by means of screw 18 and washer 19. Rotation of the finger disk 8 will cause rotation of the spring casing 12 and the extensions 14 of the spring casing will take along and rotate the gear wheel 17 correspondingly. The structure provides a satisfactory connection securing the parts for reliable rotation while requiring merely a central bore in the gear wheel, such bore being for manufacturing reasons preferably a non-circular opening.

The gear wheel 17 meshes with pinion 20 which is journaled on the spindle 3, the pinion having a bushing 21 integral therewith which is coupled to a gear wheel 22 by means of a clutch spring 23. A split ring 24 secures the gear wheel 22 against displacement in axial direction. Between the split ring 24 and a cam disk 25 which is fixedly connected with the bushing 21, there is disposed a cam 26 which is journaled on the bushing. The cam 26 is coupled with the cam disk 25 by means of a spring. A split ring 27 secures the cam disk 25 and therewith the cam 26 in assigned position on the arbor 3.

The gear wheel 22 meshes with a pinion 28 which is journaled upon the spindle 2. A carrier member 29 is connected with the pinion 28 for rotation therewith, the member 29 carrying at its opposite ends spindles indicated at 30 and 31, such spindles carrying brake shoes or weights 32 and 33 which are journaled thereon. A looped spring 34 extends below the carrier 29 about the spindle 2 out of engagement with the spindle, the looped spring having angular extensions 35 entering grooves formed in the brake shoes. The looped spring secures the brake shoes against slipping off from the spindles 30, 31, thus obviating holding means such as separate split rings or the like.

There are provided two sets of contacts respectively comprising the normal springs 37, 38 and the impulse springs 39, 40 which extend from an insulating member 36 mounted upon the base 1. The normal contacts (springs 37, 38) are controlled by a cam member 41 carried by the gear wheel 17; the impulse spring 40 is in engagement with the impulse cam of the impulse transmitting device. Brackets 42 and 43 serve for mounting the transmitter mechanism in a telephone set.

On the side facing the finger disk 8, the frame 1 is provided with a cap 44 made of insulating material, which is snapped in place by means of teeth such as 45 engag-

ing angular portions at the rim of the frame. The cap 44 carries the required numerals and/or characters such as indicated at 46. The finger stop 47 is also made of insulating material, the mounting part of such stop projecting through a slot formed in the cap 44 and being secured to the frame 1 against removal therefrom and against angular displacement relative thereto, by means of a screw 49 projecting through a hole formed in the frame 1 and a nut 48 positioned in a recess formed in the cap 44. This mounting for the finger stop also secures the cap 44 against angular displacement and loosening thereof. The free end 50 of the screw 49 projects through and beyond the cap 44 in the direction of the finger disk, forming a fixed stop for cooperation with a stop 51 carried by the finger disk and movable therewith. The stopping of the drive gear is effected by the cooperation of these stops very gently because the mass forces involved are controlled at a point of greatest magnitude thereof.

The journal or bearing surfaces and the gear wheels and pinions as well as the bushing 21, cam 26 and cam disk 25 are made of non-metallic synthetic material. The cam 41 for the actuation of the gear wheel 17 is formed integral with the coating of synthetic material carried by the metal body.

The operation of the dial is as follows:

Upon rotating the finger disk 8 out of its normal position, the restoring spring 13 will be wound up. The gear wheel 17 will be carried along in such rotation, in turn carrying along and rotating the pinion 20 and the bushing 21 axially extending therefrom. The cam disk 25 which is fixedly connected with the bushing 21 and the cam 26 which is frictionally coupled with the cam disk 25, are likewise rotated. The gear wheel 22 is coupled to the bushing 21, by the clutch spring 23, so that it is not rotated at all or only slightly displaced incident to the described winding-up rotation of the parts. The cam 26 upon being taken along is placed underneath the spring 40 and remains in such position due to its slight impositive coupling with the cam disk 25. The contact points of the impulse springs 39, 40 are in engagement and these springs are in their engaged position moved back and forth in common incident to the winding-up rotation of the finger disk but the contact engagement remains undisturbed. Accordingly, no impulses will be transmitted.

Upon rotation of the finger disk 8 from the wound-up position back to normal, the gear wheel 17 will rotate the pinion 20 and therewith the bushing 21 extending therefrom and also the cam disk 25 connected with the bushing, in opposite sense. The gear wheel 22 is now taken along by the action of the cylindrical spring clutch 23 and drives the governor by rotating the pinion 28. The cam 26 upon being taken along arrives at the front edge of the spring 40, which is slotted, one of the tongues which are formed by the slotting being shorter than the other. The spring 39 now lies with its free end above the cam which had been stopped in front of the shorter tongue. Rotation of the cam disk 25 now causes alternate opening and closing of the contact points carried by the impulse springs 39, 40 because spring 39 is held by cam 26 against following the motions imparted to spring 40.

In the normal or resting position of the finger disk 8, the contact points of springs 37, 38 will be out of engagement due to the action of cam 41 carried by the gear wheel 17. When the finger disk is rotated out of its normal position, the contact springs 37, 38 will be actuated to close their contact points up to the time when the finger disk returns to its normal position, when the contacts will again be opened.

The transmitter mechanism is covered at the bottom

thereof by a transparent cap 52, made of resilient material, such cap being provided with brackets 53 for snap-on engagement with corresponding mounting means carried by the frame 1.

Changes may be made within the scope and spirit of the appended claims in which is defined what is believed to be new and desired to have protected by Letters Patent.

We claim:

1. A telephone call transmitter comprising a frame, a first and a second spindle, each fixedly fastened at one end to said frame and freely extending in parallel relationship therefrom, impulse contact means disposed adjacent to but spaced from said first fixed spindle, cam means rotatably disposed on said first fixed spindle operatively related to said contact means for actuating the same, and a first pinion also disposed upon such spindle for driving said cam means to effect operative actuation of said contact means, a governor rotatably disposed upon such second fixed spindle and a second pinion also disposed upon such second spindle for driving said governor, a rotatable main shaft, a finger disk rotatable with said main shaft, a first toothed gear wheel carried by said rotatable main shaft, said first gear wheel meshing with said first pinion, and a second toothed gear wheel rotatably disposed upon said first spindle, said second toothed gear meshing with said second pinion and operatively connecting the latter to said first pinion.
2. A call transmitter according to claim 1, wherein said frame is a diecast part having the respective ends of said first and second spindles embedded therein and forming an integral part thereof.
3. A call transmitter according to claim 1, comprising means forming a raceway for said governor, and a device for mounting said raceway means, said device comprising an extension integral with said frame and approximately semi-circularly surrounding the spindle for said governor.
4. A call transmitter according to claim 3, wherein said raceway means is a stamped plate having a cylindrical bore formed therein for braking cooperation with a part of said governor.
5. A call transmitter according to claim 1, comprising a bushing extending axially from said first pinion integral therewith, a cam disk carried by said bushing for rotation therewith, means for coupling said second gear wheel for rotation with said bushing, and a cam coupled for rotation with said bushing.
6. A call transmitter according to claim 1, wherein the journal surfaces of said gear wheels and those of said pinions are formed by non-metallic synthetic material.
7. A call transmitter according to claim 6, comprising a control contact, and a cam member for governing the actuation of said control contact, said cam member being formed integral with the synthetic material of one of said gear wheels.
8. A call transmitter according to claim 1, wherein said main shaft carries a jacket of non-metallic synthetic material.
9. A call transmitter according to claim 1, comprising a restoring spring, a casing rotatable with said main shaft, said casing containing said restoring spring, the ends of said restoring spring being respectively anchored in said frame and in said casing, and extensions projecting from said casing into openings formed in said first gear wheel for driving such gear wheel responsive to rotation of said main shaft.
